UNITED STATES PATENT OFFICE

172,928

TOILET TISSUE HOLDER

Alta C. Jones, Elyria, Ohio

Application October 12, 1953, Serial No. 27,140

Term of patent 3½ years

(Cl. D4—3)

To all whom it may concern:

Be it known that I, Alta C. Jones, a citizen of the United States, residing at Elyria, in the county of Lorain and State of Ohio, have invented at new, original, and ornamental Design for a Toilet Tissue Holder, of which the following is a specification, reference being had to the accompanying drawing, forming part thereof.

I claim:

The ornamental design for a toilet tissue holder, as shown.
